HARD SURFACE FLOOR COVERING OR SIMILAR ARTICLE

Andrew E. Lawrence, San Mateo, Calif., assignor
to Pabco Products Inc., San Francisco, Calif.,
a corporation of Delaware

Application April 17, 1951, Serial No. 14,872

Term of patent 14 years

(Cl. D92—17)

To all whom it may concern:

Be it known that I, Andrew E. Lawrence, a citizen of the United States, residing in the city of San Mateo, county of San Mateo, State of California, have invented a new, original, and ornamental Design for a Hard Surface Floor Covering or Similar Article, of which the following is a specification, reference being had to the accompanying drawing, forming part thereof.

The drawing is a plan view of a piece of a hard surface floor covering showing my design. On such drawing, the broken lines outline a design unit which is repeated in regular succession as indicated by the extensions beyond the boundaries of such unit.

I claim:

The ornamental design for a hard surface floor

covering or similar article, substantially as shown and described.

ANDREW E. LAWRENCE.
